UNITED STATES PATENT OFFICE.

CLAUDIUS DORNIER, OF FRIEDRICHSHAFEN, GERMANY, ASSIGNOR TO THE FIRM
DORNIER METALLBAUTEN GESELLSCHAFT MIT BESCHRÄNKTER HAFTUNG, OF
FRIEDRICHSHAFEN, GERMANY.

HOLLOW BODY FOR AVIATION PURPOSES.

Application filed August 19, 1922. Serial No. 582,967.

To all whom it may concern:

Be it known that I, CLAUDIUS DORNIER, a citizen of Germany, residing at Friedrichshafen, Germany, have invented certain new and useful Improvements in Hollow Bodies for Aviation Purposes, of which the following is a specification.

My invention has reference to hollow metal bodies which are adaptable for use as floats or hulls or the like for hydroplanes, airplanes and for similar purposes, and it particularly refers among other important features to novel means for assembling the parts, as well as to the new articles of manufacture constituting some preferred embodiments of this invention. It is also an important object of my invention to facilitate the riveting and assembling of the parts of such hollow bodies, even of comparatively small sizes. These and other objects and advantages of the invention will appear as the specification proceeds.

Heretofore the floats, for example to be used for hydroplanes, were usually manufactured in the shape of open boats which were then closed by the application of separate closely adjoining sheet metal closing plates. Small apertures were merely provided for the removal of leakage water. This mode of construction is open to many objections both as regards the manufacture itself as well as regards the subsequent utilization of the hollow bodies. In order to avoid the presence of too large a number of riveting rows the covering up of the float has been effected by sheet metal plates of the width and length common in the trade. Inasmuch as the surface of the float is usually vaulted, the rigidity of the arched upper covering plate causes the inner riveting seam to be very difficultly accessible after the application of a new sheet metal section, particularly with the sizes usually met with in the case of floats for aviation purposes.

These inconveniences are avoided in this invention, and it provides means for facilitating the riveting upon the application of the upper covering plate or the deck which is usually composed of several sections, and is transversely arched, by immediately connecting the marginal sections securely with the side walls of the float, but in such a manner that a section is left freely exposed which extends from front to rear and sub-

stantially parallel to the longitudinal axis 55 of the float the said section being only closed by a covering sheet at the final stage of the manufacture. By this means a considerably simplified method of manufacture which can be easily practised, is obtained, because the 60 lateral extension sheet metal strips or sections in view of their small width and of the small camber resulting therefrom may be rolled off, so to speak, in proportion with the progress of the manufacture, particularly 65 with sheet metal of the small thickness generally employed. It is no longer necessary to leave a section running clear through from the bow to the stern entirely freely exposed, but it is preferable to provide covering and closing sheets along with the attaching of the lateral sheet metal sections at the beginning and the rear extremity of the body, and to interrupt the exposed strip section by bridge pieces spaced from each other 75 for strengthening purposes.

It is preferable to effect the securing in position of the closing metal sheets in such a manner that both the securing in position as well as the detaching of the sectional sheets 80 may be effected in an easy and rapid manner.

The invention may evidently also be applied for the purpose of facilitating the manufacture of hulls and the like flotation bodies for aviation purposes, in the manufacture of which as heretofore practised by the application of the upper covering sections or in the assembling of the hulls from individual separate annular sections the last riveting seams were difficultly accessible, 90 aside from other difficulties presenting themselves in the making of repairs.

These inconveniences may be avoided according to this invention by allowing a strip to be left free which extends in the manner 95 described approximately or substantially in parallel relation to the longitudinal axis of the hull or of the hollow body, and which is covered up by a sheet metal closing plate after the assembling of the different sections 100 has been substantially terminated. Such sheets or sections may be provided both in the upper deck portion as well as in the side walls or in the bottom wall of the hollow body.

As a further improvement my invention also makes provision for arranging the riveting seams entirely at the outside, while

the inner edges of the upper shell which has already been connected to the side walls, is curved upwardly. The covering section may be correspondingly shaped by having its edges bent upwards likewise. The confronting sheet metal edges are made to engage with each other and are then riveted together. It is particularly advantageous to apply a substantially U-shaped sectional 10 bar or the like onto the contacting edges of the sheets and to run the rivets through the edges and the said sectional bar.

The invention is illustrated upon the accompanying drawings showing by way of 15 example several forms of embodiment of the invention, as applied to floats or the like.

Figure 1 illustrates in a conventional manner a hydroplane float in vertical cross section on the line 1-1 of Figure 2 and 20

Figure 2 shows the float as seen from above.

Figure 3 shows perspectively and diagrammatically a hull for aviation purposes 25 in transverse section and

Figure 4 is a detail, showing more clearly the point of connection of the hull on a somewhat enlarged scale.

The construction of the float is substantially effected by first assembling the parts 30 so as to obtain an open boat comprising the bottom *a*, and the two side walls *b* which at their upper edges are each provided with angle pieces *c*. At the stern and the bow 35 covering metal sheets *d* and *e* respectively are applied, and at the same time the two bridge pieces *f* are inserted for the purpose of stiffening the side walls *b*. Then, in accordance with my invention the two lateral 40 strips *g* of the upper deck are applied. When using thin metal sheets the strips may be rolled off gradually in proportion 45 with the progress of the work of laying the same, so as to still further facilitate the insertion of the rivets. Even in case the metal sheets are applied as rigid units, the rivets are still easily accessible. In conclusion the float is closed by the covering sheet *h* which is also secured by rivets. In order to be 50 able to inspect the interior of the float or to ascertain any formation of bilge water or the like three openings are provided which may be closed in the usual manner by means of hand hole covers *i*.

55 The construction of the hull of the hollow body, as illustrated in Figures 3 and 4, is effected in such a manner as to leave a strip uncovered in one of the walls which extends substantially or approximately parallel to the longitudinal axis of the float and substantially from front to rear. All parts of the hull remain easily accessible even with small sizes. In conclusion the exposed strip-shaped section of the hull *h* 60 is filled up with a sheet metal plate *l* which

is preferably detachably connected to said hull. The edges of the inserted piece *l* and the edges of the hull may be bent upwards, as shown in the drawing, and a profilated or channeled bar *m* may be mounted upon 70 the joint as appears from Figure 4 of the drawing.

The invention is susceptible of various other changes and modifications so as to better adapt it for its various uses and applications, and without deviating from the spirit of the invention as defined in the claims.

In this connection the term "flotation body" used in the claims is to be construed 80 as including fuselages of aircraft or similar bodies in the manufacture of which these principles of construction may be employed.

I claim:

1. A flotation body for aviation purposes 85 comprising a hollow body having an open side, a vaulted marginal strip attached about the edge of the opening, and closure means secured to the strip completely closing the remaining open space. 90

2. A flotation body for aviation purposes comprising a hollow body of sheet metal forming bottom and side walls, narrow marginal strips extending inwardly about the side walls leaving a longitudinal opening, 95 angle members connecting the marginal strips to the side walls, and a closure plate completely closing the opening and having means enabling access to the interior for securing the closure plate in position. 100

3. The method of constructing hollow flotation bodies for aviation purposes which consists in connecting sheet metal into a substantially longitudinally extending hollow body with one longitudinally extending 105 open side, connecting marginal pieces spaced from each other around said opening and closing the remaining free space by covering means above the surface of the original opening, so as to obtain a vaulted deck 110

4. The method of constructing hollow flotation bodies for aviation purposes which consists in connecting sheet material into a substantially longitudinally extending 115 hollow body with one open side, vaultedly connecting marginal strips to said body around said open side, connecting said strips by transverse members, vaultedly covering the remaining space by covering means and securing said covering means in position. 120

5. A flotation body for aviation purposes and the like, comprising a substantially longitudinally extending endwise closed hollow body with an open side, marginal deck portions along the sides of said opening, and a vaulted upper deck member secured to said marginal portions. 125

In testimony whereof I affix my signature.
CLAUDIUS DORNIER.

Certificate of Correction.

It is hereby certified that Letters Patent No. 1,440,282, granted December 26, 1922, upon the application of Claudio Dornier, of Friedrichshafen, Germany, for an improvement in "Hollow Bodies for Aviation Purposes," were erroneously issued to the firm "Dornier Metallbauten Gesellschaft mit beschränkter Haftung, of Friedrichshafen, Germany," as assignee of the entire interest in said invention, whereas said Letters Patent should have been issued to the inventor, said *Dornier*, and to the firm *Dornier Metallbauten Gesellschaft mit beschränkter Haftung, of Friedrichshafen, Germany*, jointly, said firm being assignee of *one-half interest* only in said invention, as shown by the records of assignments in this office; and that the said Letters Patent should be read with this correction therein that the same may conform to the record of the case in the Patent Office.

Signed and sealed this 1st day of May, A. D., 1923.

[SEAL.]

KARL FENNING,
Acting Commissioner of Patents.
